UNITED STATES PATENT OFFICE.

FRANKLIN R. WHITE, OF WATERBURY, CONNECTICUT, ASSIGNOR TO THE PATENT BUTTON COMPANY, OF SAME PLACE.

DESIGN FOR AN EYELET-DIE.

SPECIFICATION forming part of Design No. 33,501, dated November 6, 1900.

Application filed September 25, 1900. Serial No. 31,104. Term of patent 14 years.

To all whom it may concern:

Be it known that I, FRANKLIN R. WHITE, a citizen of the United States, residing at Waterbury, in the county of New Haven and State of Connecticut, have invented and produced 5 a new and original Design for Eyelet-Dies, of which the following is a specification, reference being had to the accompanying drawings, forming a part thereof.

10 Figure 1 is a bottom view of an eyelet-die, showing my new design. Fig. 2 is a top plan view thereof. Fig. 3 is a sectional view taken on the line 3 3 of Fig. 2. Fig. 4 is a similar view taken on the line 4 4 of Fig. 2.

15 The leading or material feature of my design consists of a shell having inwardly-curved points and a depressed top, the well or de-

pression being downwardly curved between the curled points.

A represents the die, provided with upwardly and inwardly curled points B, the top of the die having a curved depression C extending downwardly between the curled points B.

What I claim is—

The design for an eyelet-die, as herein shown and described.

Signed at Waterbury, in the county of New Haven and State of Connecticut, this 10th day of September, A. D. 1900.

FRANKLIN R. WHITE.
